United States Patent Office.

FRANKLIN J. STALEY, OF INDIANAPOLIS, INDIANA, ASSIGNOR TO HIMSELF, GEORGE W. JOSEPH, ISAAC S. LONG, AND GEORGE H. CARTER, OF SAME PLACE.

Letters Patent No. 98,215, dated December 21, 1869.

IMPROVEMENT IN HEAD-BLOCKS OF SAW-MILLS.

The Schedule referred to in these Letters Patent and making part of the same.

I, FRANKLIN J. STALEY, of Indianapolis, in the county of Marion, and State of Indiana, have invented certain Improvements in Head-Blocks for Saw-Mills, of which the following is a specification.

Nature and Objects of the Invention.

My invention relates to construction and arrangement of the device attached to and constituting part of the head-blocks of saw-mills, combined with the longitudinal setting-shaft usually employed for operating the knees, and a ratchet-wheel and lever and series of pawls arranged to actuate the setting-shaft, in such a manner that both knees may be moved simultaneously toward the saw, as in sawing lumber of equal thickness, and so that either knee may be moved toward the saw while the other remains at rest, as in sawing tapering lumber, or logs that are larger at one end than the other and also so that the knees may be moved in like manner quickly backward or from the saw into position to receive another log, the object being to have a more complete and ready control over the movement of the knees, for the purpose of setting the log, than heretofore.

Description of the Accompanying Drawings.

Figure 1 is an elevation of a log-carriage and head-blocks embodying my invention.

Figure 2 is a plan view of the same.

Figure 3 is a detail vertical longitudinal section of the device attached to and forming part of the head-blocks for actuating the knees.

Figure 4 is a transverse section of the same, showing the inside of one of the flanges with the pawl and spring attached.

Figure 5 is an exterior view of one of the flanges.

General Description.

A is the log-carriage, made and operated in the usual manner.

B, the head-blocks, furnished with knees C, in the usual manner.

The device for operating the knees to set the log consists of the longitudinal setting-shaft D, which passes through a sleeve E, fitting neatly but working freely therein, and having collars F on the ends, one of which is made permanent and the other to screw on so as to be removable.

Keys e e pass through the sleeve, the inner ends projecting into a key-seat cut the entire length of the shaft. These keys prevent the sleeve and collars from turning on the shaft, and at the same time are so arranged as to allow the position of the head-blocks to be changed along the log-carriage, to adapt it to logs of different lengths, at pleasure.

Surrounding the sleeve E is a casting, G, that fits neatly and works freely thereon. The casting G has

cogs i around its centre, that gear with cogs on the under side of the knees. The outer ends of casting G are furnished with ratchet-cogs o, and between the ratchet-wheels and the centre cogs are the bearings r, in the sides of the head-blocks.

s s', fig. 2, are pawls pivoted to the collars F, that engage with the ratchets o, the latter being arranged to work in opposite directions, the one on the left operating to move the knees from the saw, and that on the right moving them toward the saw.

The setting-shaft D is operated by double pawls, H and I, attached to the hand-lever J, the pawls engaging with the large ratchet-wheel K, on the shaft of which is a bevel-wheel, L, that gears with a bevel-wheel, M, on the setting-shaft.

Bevel-wheel M is made so as to be disengaged from wheel L, in the usual manner of arranging such wheels, by means of the lever N.

By operating the lever J, the setting-shaft is rotated, carrying with it the sleeve E and collars F, the pawl s', on the right collar, engaging with the ratchet o on that end of the casting G, and rotating the centre cogs i, to move the knees toward the saw.

The pawls H and I are made in pairs, one of which in each pair is made half the length of a tooth shorter than the other.

By this arrangement the teeth in ratchet-wheel K can be made double the size that would otherwise be required, thereby securing greater strength and durability of the teeth.

The movement of the lever J is regulated by a pin inserted in the holes R, in the segmental guides Q, which are so arranged, in combination with the double pawls H and I, and ratchet-wheel K, as to regulate the movement of the knees to any desired fraction of an inch, the advantage of which will be readily appreciated by the users of saw-mills.

By disengaging the pawl s', on the right of either of the head-blocks, and then operating the lever J, the ratchets o and cogs i will not be turned, and hence the knees of that block will remain motionless, while the knee of the other head-block will be moved toward the saw as usual, thus enabling me to set the log to any required angle to the saw, as may be required in sawing tapering lumber, or logs that are larger at one end than at the other.

By disengaging the bevel-wheel M, the shaft D may be turned by the hand crank-wheel P, and the knees be thus moved quickly into position to receive another log, or for other purposes.

The knees may also be moved back from the saw by hand, by disengaging the pawl s', on the right of the head-blocks.

I claim, as my invention—

1. The sleeve E, furnished with the flanges F and pawls s s' and keys e e, concentric piece E, furnished

with cogs *i* and ratchets *o*, in combination with the setting-shaft *D*, furnished with the hand crank-wheel *P* and knees *C*, all constructed and arranged substantially as and for the purpose set forth.

2. The ratchet-wheel *K*, lever *J*, pawls *H* and *I*, arranged in pairs, as described, in combination with bevel-wheels *L* and *M*, setting-shaft *D*, and the device described, for operating the knees *C*, constructed and arranged substantially as and for the purpose set forth.

3. The segmental arch *Q*, lever *J*, pawls *H*, *I*, ratchet *K*, and gears *L* and *M*, when all the parts are constructed and arranged as herein specified, and for the purpose set forth.

FRANKLIN J. STALEY.
